UNITED STATES PATENT OFFICE.

JOSEPH FERRETTI, OF JERSEY CITY, NEW JERSEY.

STRINGED MUSICAL INSTRUMENT.

1,275,667.

Specification of Letters Patent. Patented Aug. 13, 1918.

Application filed June 7, 1917. Serial No. 173,400.

To all whom it may concern:

Be it known that I, JOSEPH FERRETTI, a citizen of the United States, residing at Jersey City, in the county of Hudson and State 5 of New Jersey, have invented certain new and useful Improvements in Stringed Musical Instruments; and I do hereby declare the following to be a full, clear, and exact description of the invention, such as will enable others skilled in the art to which it 10 appertains to make and use the same.

This invention relates to a novel and improved violin and more particularly to a single stringed instrument.

15 The invention has for an object to provide a stringed musical instrument having novel means for reproducing and amplifying the sound thereof and causing the same to be projected in the most suitable and 20 desired direction.

Other and further objects and advantages of the invention will be hereinafter set forth and the novel features thereof defined by the appended claims.

25 In the drawing,

Figure 1 is a top plan of the instrument.

Fig. 2 is a side view thereof, and

Fig. 3 is a sectional detail view of the sound box attached.

30 Referring to the drawings, wherein similar reference characters denote corresponding parts throughout the several views, 1 denotes the top of the body of the instrument, 2 the bottom thereof suitably spaced from the top and 3 the side wall of the instrument which connects the edges of the top 1 and bottom 2. The body of the instrument may be of any desired shape but preferably that shown in the drawings, and suitably secured upon one end of the body is 35 the neck 4 provided with the fingerboard 5 and the head 6, in which is rotatably mounted the key or tuning pin 7.

Upon the side wall 3 at one end of the body of the instrument is the knob 8 to which is attached one end of the string 9, which passes over the tail piece 10 secured upon the top 1 above the knob thence over the bridge 11 and the nut 12 into the slot 13 45 formed in the head 6 where the end of the string 9 is secured to the tuning pin 7 for drawing the string 9 to the proper pitch.

50 Formed at any suitable point within the top 1 is the opening 14, preferably of rectangular shape, and also formed in the bottom 2, is the small opening 15, preferably

circular and disposed at any suitable point beneath the opening 14 in the top. Secured upon the underside of the bottom 2 by the screws 16, or other suitable securing means, 60 and surrounding the opening 15 in the bottom 2 is the annular flange 17 of the elbow 18 of the horn 19 provided with the outwardly flared or bell-shaped end 20.

Projected through the opening 14 in the top 1 of the body of the instrument and disposed therein is the body 21 of the sound box, which is preferably rectangular in shape and has its upper end open, but the bottom 22 of the sound box 21 is provided 65 preferably centrally thereof with the bell-mouthed end 23 of the sound conducting tube 24 which projects through the opening 15 in the bottom 2 and into the adjacent end of the elbow 18 of the horn 19. Upon 70 the sound box 21, at any suitable and desired point, are the plurality of apertured ears 25 through which project the securing bolts 26 for securing the sound box 21 to its cover plate 27. The heads 28 of the securing bolts 26 are preferably counter sunk in the cover plate 27, which is of greater length and width than the sound box 21 so that the projecting edges of the cover plate 27 will rest upon the upper surface of the top 75 1 of the instrument. For securing the cover plate 27 and the sound box 21 in operative 80 position within the opening 14 of the top 1 and the sound box within the interior of the body of the instrument, the cover plate 90 27 is provided at its ends with the apertured ears 29 through which are inserted the screws 30, or other suitable securing means entering the top of the instrument.

Within the lower portion of the sound box 21 is the gasket or square ring 31, and also mounted within the upper portion of the sound box 21 is a similar ring 32, the rings 31 and 32 being formed of any suitable material, preferably rubber. Interposed between the rings 31 and 32 are the edges of the disk or diaphragm 33 which is securely held by the binding action of the rings when the sound box 21 and its cover plate 27 are secured together through the bolts 26, and 95 upon the diaphragm 33 rests the lower portion of the bridge 11 which projects through the elongated opening 34 formed preferably centrally through the cover plate 27.

100 The string 9 is vibrated by any suitable bow drawn backward and forward there-across and the vibrations of the string thus

produced are conducted through the bridge and diaphragms to the megaphone.

Having described my invention, what I claim as new and desire to secure by Letters Patent is:—

1. A stringed musical instrument comprising a hollow body, a neck thereon, a string upon said body and neck, a sound box supported from the upper surface of 10 and depending within said body, an apertured cover plate for said box, a diaphragm within said sound box, a bridge carried by said diaphragm and extending through said cover plate for supporting said string, and 15 a horn upon said hollow body and communicating with said sound box.

2. A stringed musical instrument comprising a hollow body thereon, a string upon said hollow body and said neck, a sound box

disposed within said body, an apertured 20 cover plate for said box secured to the body, clamping means extending from said cover plate to said box for retaining the same in position, packing rings at the edges of said box, a diaphragm disposed within said box 25 between said rings, a bridge carried by said diaphragm and extending through said cover plate for supporting said string, and a horn upon said hollow body communicating with said sound box.

In testimony whereof I have signed my name to this specification in the presence of two subscribing witnesses.

JOSEPH FERRETTI.

Witnesses:

JOHN BUSCH,
WM. KILLEEN.
